UNITED STATES PATENT OFFICE.

HOWARD A. YOUNG, OF CHICAGO, ILLINOIS.

VACUUM-PRODUCING SYSTEM.

1,287,169.

Specification of Letters Patent. Patented Dec. 10, 1918.

Application filed December 14, 1917. Serial No. 207,198.

To all whom it may concern:

Be it known that I, HOWARD A. YOUNG, a citizen of the United States, residing at Chicago, in the county of Cook and State 5 of Illinois, have invented certain new and useful Improvements in Vacuum-Producing Systems, of which the following is a specification.

This invention relates in general to means 10 for producing a vacuum or a partial vacuum, and the embodiment of the invention herein disclosed relates particularly to a system for producing a vacuum in a pipe which, in the present instance, is the return 15 pipe of a vacuum steam heating system of the direct return type.

In heating systems of this character air and other non-condensable gases must be withdrawn from the radiators together with 20 a variable amount of water vapor and condensed water which collects in the radiators and the pipes.

Since a centrifugal pump is incapable of handling both air or gas and liquid with any 25 appreciable degree of satisfaction it is now the common practice to utilize reciprocating pumps for producing the requisite vacuum in the return pipes of steam heating systems of the character above indicated.

Reciprocating pumps, however, must necessarily be driven at a relatively low rate of speed, and since the almost universally used motive power is now electricity the driving 30 connection between the motor and the reciprocating pump involves a train of back gearing which is objectionable because of 35 its noisy operation.

It has also been proposed that two centrifugal pumps be used directly connected to the 40 motor so as to eliminate the noisy gearing. One of these pumps being designed to draw the air and gas and produce the vacuum while the other pump is designed to discharge accumulated water back into the 45 boiler or wherever it is desirable that it be utilized. Such a system possesses low efficiency for the reason that it necessitates the continuous operation of two pumps, whereas it is highly desirable that but one be employed.

My present invention contemplates the utilization of a single centrifugal pump which may be directly connected to an electric motor, thus eliminating a gear drive, 55 the system being so designed that this pump operates continuously upon liquid so that it

runs under a constant load at maximum efficiency, the liquid discharged from the pump being utilized to produce the vacuum in the return pipe of the heating system and the 60 air and gas drawn from this pipe being permitted to escape to the atmosphere while the liquid withdrawn from the pipe is intermittently and automatically discharged by the same pump into the boiler or other 65 desired place of use.

In order to facilitate an understanding of my invention I have illustrated on the accompanying sheet of drawings one preferred embodiment thereof, which drawing 70 should be considered in connection with the following description.

The single figure of the drawing represents in side elevation a portion of a heating system to which one preferred embodiment 75 of my invention is applied.

Referring to the drawing, reference character 5 indicates a reservoir or container of suitable size and shape, the one shown being substantially of pear shape, which I have found to be a practical design, and this reservoir is supported in upright position upon a suitable base 6 so that the major portion of the reservoir projects upwardly above the centrifugal pump 7. This pump may be of 80 any well known or preferred design suitably mounted upon the base 8, and the intake pipe 9 therefor is connected with the lower portion of the reservoir 5, as shown. The discharge pipe 11 from the pump 7 is connected with the upper portion of the reservoir 5 so that a closed liquid circulating system or circuit is established through the reservoir 5, intake pipe 9, pump 7, and discharge pipe 11. When the apparatus is assembled the reservoir 5 is supplied with water through the top after the cover 12 has been removed until the water level is at least as high as the lower water level 13 indicated on the drawing, with the result that the 85 pump 7 is entirely submerged in liquid, so that it is always primed and ready to operate when the motor is started.

An injector 14 consisting, preferably, of a nozzle 15 discharging through a restriction, 90 is interposed in the discharge pipe 11, so that when the pump is in operation the liquid discharged thereby will create and maintain a constant partial vacuum in the pipe 16 connected to the suction connection 110 of the injector. It should be obvious that when the pump is in operation a constant

suction will be maintained by the injector action in the pipe 16, the amount of which will be dependent upon the speed of the pump.

- 5 The pipe 16 in the present instance is the return pipe of a vacuum steam heating system and is shown as connected to one of the radiators 17 in the usual manner, it being understood of course that steam is supplied 10 to this radiator and the other radiators in the system directly from a boiler in the usual and well known manner. The suction created by the injector, as the result of the operation of the pump, will withdraw from 15 the heating system through the pipe 16, the air, gas, water vapor and liquid, all of which accumulate in varying amounts in the heating system. The amount of water will depend upon the amount of condensation in 20 the system and the amount of steam supplied thereto, and consequently the amount of liquid withdrawn through the pipe 16 continually varies. All of the air, gases and liquids withdrawn through the pipe 16, 25 however, will be delivered through the pipe 11, along with the water discharged from the pump 7, into the reservoir, where the air and gases will be permitted to escape to the atmosphere through a vent pipe 17.
- 30 The accumulation of liquid in the reservoir will necessarily raise the liquid level therein and when a predetermined surplus has been accumulated this surplus will be discharged under pressure to the boiler or 35 other desired place of use, as will be now described.

In the reservoir upon a rock shaft 18 I have mounted upon a laterally extending arm a float 19 which, as the liquid level 40 rises to substantially the upper level indicated by reference character 21 on the drawing, will rock the shaft 18 so as to elevate the arm 22, rigidly mounted thereon, thereby through a link or rod 23 opening a balanced valve of any preferred construction 45 mounted in the casing 24 which is interposed in a branch pipe 25 leading from the discharge end of the pump 7. The connection between the link 23 and the arm 22 is 50 a lost motion connection, as shown, so that when once the valve is opened it will remain in open position until the liquid level in the reservoir 5 has fallen a predetermined amount, whereupon the valve 24 will be 55 closed, and will remain in closed position until a predetermined maximum liquid level has been reached. Since the pipe 25 is connected to the discharge end of the pump it will be manifest that the liquid discharged 60 through this pipe when the valve 24 is open, will be delivered under considerable pressure and may therefore be delivered directly into a boiler without the employment of a second or auxiliary pressure pump.

65 It should be manifest from the foregoing

that I have provided a system which will create and maintain a constant vacuum in the return pipe 16 and will withdraw from this pipe, air, gas and liquid, irrespective of the amounts or relative proportions of each, that the air and gases are permitted to escape while the liquid is conserved and permitted to accumulate in the reservoir until a predetermined amount has been collected, whereupon this surplus is automatically delivered under pressure to any desired point. Furthermore, the pump is required to handle liquid only and therefore operates under a uniform load so that it will run evenly and at maximum efficiency at all times. It will be noted that the capacity of the pipe 25 is restricted relative to that of the discharge pipe 11 from the pump with the result that regardless of the opening or closing of the valve 24, the vacuum will be maintained because of the continuous flow of water through the pipe 11. While I have shown and described my invention as connected with a steam vacuum heating system it should be manifest that it is capable of use for producing vacuum for other purposes, and it should also be understood that considerable variation in the size, shape, proportion and arrangement of the various elements constituting my invention may be resorted to without departing from the spirit of the invention or sacrificing any of its material advantages.

I claim:

1. In a vacuum producing system, the combination of a centrifugal pump, a liquid container extending above said pump, an intake pipe connecting the lower portion of said container with said pump, a discharge pipe leading from the pump to the upper portion of said container, an injector interposed in said discharge pipe, a return pipe from a heating system connected with the suction side of said injector, and means for automatically permitting liquid under the pressure of said pump to flow from the discharge pipe at a point between the pump and the connection between the return pipe and injector, when a predetermined liquid level is reached in said container.
2. The combination of a liquid circulating system, including a container and a rotary pump having its suction and discharge ends connected with the lower and upper ends respectively of said container, an injector through which the liquid delivered from the pump into the container passes, the suction side of the injector being connected with the return pipe of a steam heating system or the like, so that liquid and gas are drawn from said pipe and delivered to said container, a liquid delivery pipe connected with the discharge pipe from the pump at a point between the pump and injector, a valve in said delivery pipe, and means con-

trolled by the height of liquid in said container for actuating said valve.

3. The combination of a liquid circulating system, including a container and a rotary pump having its suction and discharge ends connected with the lower and upper ends respectively of said container, an injector through which the liquid delivered from the pump into the container passes, the suction of the injector being connected with the return line of a steam heating system or the like, so that liquid and gas may be drawn from said pipe and delivered to said container, a liquid delivery pipe adapted to be connected with the heating system, said delivery pipe communicating with the discharge from the pump at a point in advance of the injector, an automatically controlled valve for said delivery pipe, and said delivery pipe being of a restricted area relative to that of the discharge connection between the pump and container.

4. The combination of a heating system, a rotary pump, a container for liquid, a conduit leading from the container to the pump whereby the pump is maintained submerged in liquid, a discharge conduit leading from the pump back to the container, a steam heating system having a return pipe connecting with the discharge conduit of the pump, an injector in said discharge conduit adjacent the point of connection with said return pipe, and an automatic valve controlled fluid delivery pipe connecting with the discharge pipe and of a reduced area relative to the latter, said delivery pipe connecting with said discharge conduit at a point between the pump and the injector.

5. In a vacuum producing system, the combination of a container, a pump, a conduit interposed between the pump and the lower portion of the container, for supplying water to the pump, an auxiliary conduit interposed between the pump and the upper portion of the container, an injector interposed in the auxiliary conduit, a return pipe from a heating system or the like connected with the auxiliary conduit adjacent said injector, a delivery pipe adapted to be connected with a boiler or the like leading from the auxiliary conduit at a point between the pump and the injector whereby to return to the boiler or the like liquid under the pressure of said pump.

55 6. In a vacuum producing system, the combination of a reservoir having an outlet for the escape of vapor and gases, a pump, a

conduit establishing communication between the pump and the lower portion of the reservoir, a return pipe from a heating system for discharging gases and water of condensation, an auxiliary conduit leading from the pump to the upper portion of the reservoir and connected intermediate its ends with said return pipe whereby to discharge into the upper portion of the reservoir the water of condensation and gases, an injector interposed in the auxiliary conduit at the point of connection with the return pipe and a delivery pipe adapted for communication with the boiler or the like connecting with the auxiliary conduit at a point between the pump and return pipe.

7. In a vacuum producing system, the combination of a reservoir having an outlet for the escape of vapor and gases, a pump, a conduit establishing communication between the pump and the lower portion of the reservoir, a return pipe from a heating system for discharging gases and water of condensation, an auxiliary conduit leading from the pump to the upper portion of the reservoir and connected intermediate its ends with said return pipe whereby to discharge into the upper portion of the reservoir water of condensation and gases, an injector interposed in the auxiliary conduit at the point of connection with the return pipe and a delivery pipe adapted for communication with the boiler or the like connecting with the auxiliary conduit at a point between the pump and return pipe, a valve for regulating the discharge through said delivery pipe, and means for automatically controlling said valve by the supply of liquid in the reservoir.

8. In a pump apparatus for supplying water to a boiler or the like and creating vacuum in the heating system connected therewith, the combination of a reservoir, a heating system having a return pipe, a conduit in communication with the return pipe of the heating system and reservoir, a pump for supplying water from the reservoir and feeding the same through said conduit back to the reservoir whereby to create a vacuum and force the vapors and gases and water of condensation from the return pipe back to the reservoir, said reservoir having an opening for the free escape of vapors and gases from the reservoir, and a fluid delivery pipe in communication with the conduit.

HOWARD A. YOUNG.
